United States Patent Office

Des. 181,812
Patented Dec. 31, 1957

181,812

COMBINED COFFEE POT, CREAM PITCHER, AND SUGAR CONTAINER

Seymour Robins, New York, N. Y.

Application April 3, 1956, Serial No. 40,890

Term of patent 14 years

(Cl. D44—26)

I claim:

The ornamental design for a combined coffee pot, cream pitcher, and sugar container, substantially as shown.
